UNITED STATES PATENT OFFICE.

THOMAS DILL, OF BAY CITY, ASSIGNOR TO JAMES CLEMENTS, OF ANN ARBOR, MICHIGAN.

HOISTING-ENGINE.

SPECIFICATION forming part of Letters Patent No. 244,716, dated July 19, 1881.

Application filed January 13, 1881. (No model.)

To all whom it may concern:

Be it known that I, THOMAS DILL, of Bay City, in the county of Bay and State of Michigan, have invented a new and useful Improvement 5 in Hoisting-Engines, of which the following is a specification.

In the drawings, Figure 1 is a side view of my invention as applied to an excavating-machine with the cylinder and piston in section. 10 Fig. 2 is a top sectional view on line *x* *x* in Fig. 1.

My invention consists of a hoisting-engine in which the piston rocks instead of rotating, and in which the hoisting-drum is actuated by 15 a shaft rigidly secured to the pivotal point of the piston, with or without the intervention of gearing.

A is a circular steam-cylinder, secured to a foundation by suitable braces, as shown at F.

20 B is a small cylinder concentric with A, and turning steam-tight in A.

C is piston cast on or fastened on cylinder B, and moving with cylinder B.

D is a partition or cylinder-head cast on the 25 inner side of cylinder A, or otherwise securely fastened therein, making a steam-tight wall in cylinder A. The inner end of partition or wall D is properly packed so as to make a steam-tight joint with cylinder B, and the sides and

30 outer end of piston C are properly packed, so that the piston will move steam-tight in cylinder A. As the partition D is immovable and the piston C is rigidly fastened to cylinder B, it will be at once seen that this is not a ro- 35 tary engine, and that the piston can never make a complete revolution. I prefer to set partition D at the angle shown in the drawings, so that when piston C is turned as far as possible in the direction of the arrow its face will

40 be parallel with the face of partition D, to partially guard against breakage of piston C by its coming in contact with partition D.

O is an air-vent in cylinder A, through which the air can escape when the piston is forced in the direction indicated by the arrow.

45 I is a valve for admitting steam to or exhausting from cylinder A, and is worked by a lever, G, and connecting-rod H.

L is a valve similar to I, for admitting steam

to or exhausting from cylinder A. The partition D is between the ports controlled by the valves I and L, respectively, so that said valves will admit steam when opened on opposite sides of piston C.

T is a bell-crank lever connected with valve L, and so placed that whenever the piston C passes any fixed point a tappet, S, carried on shaft E, will strike the lower arm of bell-crank lever T and open valve L and admit steam into cylinder A, so as to check the motion of and cushion piston C. A spring connected with the bell-crank lever T holds valve L closed, except when the bell-crank lever T is moved by tappet S or by the engineer. Valve L may also be operated by a lever and connecting-rod when its use is desired to return piston C to its starting-point; but in ordinary use it is not necessary to use valve L, except as a safeguard against breaking piston C, as the weight of the device used for holding the articles to be raised will ordinarily return piston C when not opposed by steam-pressure. Vent O may also have a valve connected with a bell-crank lever, so that when piston C passes the position shown in dotted lines, or any determined 70 position, tappet S will close the valve to vent O, and thus cause the air in cylinder A to act as a cushion for the piston.

E is a shaft, attached firmly to piston C at its pivotal point, and rocked by piston C.

R is a wheel or drum for winding up the hauling-chain, and is actuated by shaft E, with or without the intervention of gearing, as the work to be done may require. The wheel R may be made with two grooves in its face, so 85 that two chains may be used, if desired. Tappet S may be rigidly fastened to wheel R when this is fastened on shaft E.

The operation of my engine is as follows: Vent O being open and valves I and L being 90 closed, valve I is opened by the engineer and steam is admitted to cylinder A. The steam coming in between partition D and the piston C will force the piston in the direction shown by the arrow, turning shaft E and winding up 95 the hauling-chain on drum or wheel R. When the load to be lifted has been raised far enough valve I is closed by the engineer, and the

steam in cylinder A keeps the load suspended while the load is being swung to its place of destination or dumped. As soon as the load is in place, valve I is turned by the engineer 5 so as to exhaust steam from cylinder A through the exhaust-pipe M, which is connected with the valve I opposite the steam-supply pipe K, and by this means piston C returns to its starting-point, either by the weight of the device 10 used to hold the load, or by steam-pressure admitted through valve L.

Heretofore rotary steam-engines have been provided with two abutments and a shaft provided with oscillating pistons, live steam being 15 admitted alternately on opposite sides of one of the abutments to partially rotate said pistons in reverse directions. Further, a rotary steam-engine has been provided with a shaft having radial pistons continuously revolving 20 in one direction, a cam on one end of the shaft serving to act on a steam-supply valve to admit steam to the pistons, said valves automatically closing as soon as the cam passes them, thereby permitting the steam to act by expansion 25 in the steam-cylinder. Such features, however, do not constitute my invention, and are not claimed by me.

What I claim as my invention, and desire to secure by Letters Patent, is—

30 1. In a hoisting-engine, the combination, with a steam-cylinder having an immovable partition, and a horizontal shaft provided with in the cylinder with a piston, and having a winding-drum arranged on the exterior of the

cylinder, of a valve connected with the steam-cylinder, and both with a steam-supply pipe and a steam-exhaust, and mechanism connected with said valve and controllable by an attendant, for supplying and exhausting steam to and from the cylinder, substantially as and for 35 the purpose described.

2. In a hoisting-engine, the combination, with the steam-cylinder A, immovable partition D, center B, piston C, and horizontal shaft E, provided with an exterior winding-drum, 40 of a valve, I, connected with the steam-cylinder, and with a steam-supply pipe, K, and a steam-exhaust pipe, M, and a pivoted lever, and connecting-rod between said lever and the valve, substantially as shown, whereby the 45 valve is placed under control of the attendant, for supplying and exhausting steam to and from the cylinder, as set forth.

3. In a hoisting-engine, the combination, with the cylinder A, immovable partition D, 50 piston C, and horizontal shaft E, provided with the exterior winding-drum, of two disconnected valves, I and L, both communicating with a steam-supply pipe, K, and the valve I, communicating also with an exhaust-pipe, 55 M, and mechanism connected with the valve I and controllable by the attendant, for supplying and exhausting steam to and from the steam-cylinder, all substantially as described.

THOMAS DILL.
